George Edward Griffith and Jose R. Cid, Mexico City, Mexico, assignors to Colgate-Palmolive Company, New York, N.Y., a corporation of Delaware

Filed July 15, 1966, Ser. No. 3,086

Claims priority, application Mexico Mar. 17, 1966

Term of patent 3½ years

(Cl. D73—1)

FIG. 1

FIG. 3

FIG. 1 is a perspective view of a bar of soap or similar article embodying our new design and showing the top face, side and one end thereof;

FIG. 2 is a bottom plan view of our bar of soap or similar article as seen from the face not visible in FIG. 1; and

FIG. 3 is an end elevational view of our bar of soap or similar article as seen from the end not visible in FIG. 1, when the bar of soap is resting on the visible side.

We claim:

The ornamental design for a bar of soap or similar article, as shown and described.
